UNITED STATES PATENT OFFICE.

MARTIN M. McNELEY, OF DES MOINES, IOWA, ASSIGNOR OF ONE-THIRD
TO A. L. ALLEN AND TWO-THIRDS TO M. J. SCHERMERHORN, OF DES
MOINES, IOWA.

APPARATUS FOR OPERATING RAILWAY-SWITCHES.

No. 823,136.

Specification of Letters Patent.

Patented June 12, 1906.

Application filed September 29, 1905. Serial No. 280,645.

To all whom it may concern:

Be it known that I, MARTIN M. McNELEY, a citizen of the United States, residing at Des Moines, in the county of Polk and State of Iowa, have invented a new and useful Apparatus for Operating Railway-Switches, of which the following is a specification.

My object is to prevent difficulties and delays incident to switching cars from one track to another.

My invention consists in the apparatus composed of elements and subcombinations, as hereinafter set forth, pointed out in my claims, and illustrated in the accompanying drawings, in which—

Figure 1 is a plan view that shows the position of my switch-operating mechanism relative to the main-track rails, the side-track rails, the pivoted switch-rail, and a guard-rail. Fig. 2 is a vertical longitudinal sectional view of the front end portion of a car that shows that part of the apparatus that is applied to and carried by the car for operating the switch mechanism located on the track, as shown in Fig. 1. Fig. 3 is a bottom view of the end portion of a car in dotted line and shows the car axle and wheels on its end and the switch-operating mechanism in solid lines and their positions relative to each other. Fig. 4 is a longitudinal sectional view of a flanged bed-plate and cover and bell-crank lever that has an upright at one end and is fulcrumed to a spring that normally retains the upright elevated, but also allows it to be depressed when trod upon by an animal or a wagon-wheel.

The numerals 10 and 12 designate the main parallel track rails; 13 and 14, the branch or side track rails; 15, the pivoted rail-section, and 16 a guard-rail arranged and combined in a common way. A flanged metal base-plate 18 is fitted under the main rail 10 at some distance from the plate 17 for supporting operative mechanisms. To the top of the plate 17 are pivoted bell-crank levers 19 and 20, and they are connected with a cross-piece 21, fixed to the under side of the free end of the pivoted rail-section 15 by means of links 22, as shown in Fig. 1. To the plate or bottom portion of the box 18 are fixed leaf-springs 23 and 24, and to their free end portions, that are bent upward, as shown

in Fig. 4, are pivoted bell-crank levers 25 and 26, that have uprights 27 at their free ends, as shown in Fig. 4. Rods 28 connect the pairs of bell-crank levers thus arranged relative to each other and the track-rails in such a manner that all the bell-crank levers can be simultaneously vibrated by a device carried on a car, that will impart lateral motion to one of the uprights 27 when desired by an operator on the car as it passes over the uprights and the switch.

To move the uprights 27 as required for adjusting the pivoted rail-section 15, pairs of elbow-shaped levers 29, having lateral bends 30, are pivoted in bearings 31, fixed to the under side of a car, as shown in Figs. 2 and 3, and connected with cross-bars 32 at their upper ends.

Treadles 33 are pivoted to bearers 34, fixed to the under side and center of the end portion of a car and connected with the front and upper ends of the levers 29 and the cross-bars 32.

The downwardly-inclined portions of the levers 29 are connected with the bottom of the car by means of coil-springs 36, that will allow vibratory motion to the levers and the cams 37 on their lower ends whenever the treadles 33 are depressed by the foot-pressure of a person on the car.

The plate or box 18 has an opening in its bottom that allows the bell-crank levers 25 and 26 to be depressed as required to lower the uprights 27 to be pressed down by the tread of an animal or wagon-wheel in passing over them. A cover 37 may be fitted on the box 18.

In the practical use of my invention when the pivoted rail-section 15 is in position, as shown in Fig. 1, and the operator on the car treads down the left-hand treadle 33 the cam 37 on the end of the lever 29 will be lowered as required to engage the upright 27 and press it inward toward the rail 10, and in so doing the bell-crank levers 25 and 19 will be vibrated and the free end of the pivoted rail-section 15 moved toward the guard-rail 16 and the switch thus opened for a car to advance from the main-track rails 10 and 12 onto the side-track rails 13 and 14. A reverse movement of the pivoted rail-section 15 occurs when the right-hand treadle 34 is

depressed by the operator's foot to close the switch when open as required to advance the car on the main-track rails 10 and 12.

Having thus set forth the purpose of my invention and the construction, function, and arrangement and combinations of all the parts of the apparatus and the manner of its use, the practical operation and utility thereof will be readily understood by persons familiar with the art to which it pertains.

What I claim as new, and desire to secure by Letters Patent, is—

1. In an apparatus for operating a railway-switch, a bell-crank lever having a fixed upright at one end pivoted at the side, of a main railway-track a second bell-crank lever on the opposite side of the same track, levers on a car having cams to engage the uprights and thereby vibrate the bell-crank levers alternately in reverse ways and treadles on the car for alternately operating said levers.

2. In an apparatus for operating a railway-switch, a pivoted rail-section, a bell-crank lever connected with the free end of said rail-section and means to actuate the bell-crank lever, a second bell-crank lever at some distance from the first one, a rod connecting the two bell-crank levers and means to simultaneously actuate the two bell-crank levers and the pivoted rail-section, as set forth.

3. In an apparatus for operating a railway-switch, a leaf-spring fixed to a base-plate, a bell-crank lever pivoted to the end of the spring and provided with a fixed upright at one end and means for vibrating the bell-crank when a car passes over the upright.

4. In an apparatus for operating a railway-switch, a leaf-spring fixed to a base-plate, a bell-crank lever pivoted to the end of the spring and provided with a fixed upright at one end and means for vibrating the bell-crank lever when a car passes over the upright and an opening in the base-plate to allow the upright on the end of the bell-crank lever to be depressed as set forth.

5. In an apparatus for operating a railway-switch, two parallel main-track rails, two side-track rails, a pivoted rail-section, a fixed guard-rail, two pivoted bell-crank levers connected with the free end of the pivoted rail-section, two leaf-springs fixed to a base at some distance from the pivoted rail-section, bell-crank levers pivoted to the free ends of the springs and uprights at the front ends of the bell-crank levers, to operate as set forth.

6. In an apparatus for operating a railway-switch, two parallel main-track rails, two side-track rails, a pivoted rail-section, a fixed guard-rail, two pivoted bell-crank levers connected with the free end of the pivoted rail-section, two leaf-springs fixed to a base at some distance from the pivoted rail-section, bell-crank levers pivoted to the free ends of the springs and uprights at the front ends of the bell-crank levers and means carried on a

car to engage said uprights, to operate as set forth.

7. In an apparatus for operating a railway-switch, a lever fulcrumed to the under side and end portion of a car, a cam on the lower free end of the lever and means for lifting the front end of the lever for lowering the cam to engage an upright on the end of a bell-crank lever located at the side of a track-rail and operate as set forth.

8. In an apparatus for operating a railway-switch, two levers fulcrumed to the under side and end portion of a car, a cam on the lower free end of each lever and means on the car for lifting the front ends of the lever and lowering the cams and bell-crank levers at the opposite sides of a track-rail provided with uprights at one end to be engaged by said cams when the car passes over the track as set forth.

9. In an apparatus for operating a railway-switch, a lever fulcrumed to the under side and end portion of a car, a cam on the lower free end of the lever, a spring fixed to the lever and to the car to normally retain the cam on the end of the lever elevated and means for lifting the front end of the lever for lowering the cam to engage an upright on the end of a bell-crank lever located at the side of a track-rail and operate as set forth.

10. In an apparatus for operating a railway-switch, a lever fulcrumed to the under side and end portion of a car, a cam on the lower free end of the lever, a spring fixed to the lever and to the car to normally retain the cam on the end of the lever elevated, a treadle pivotally connected with the car and upper end of the lever and means for lifting the front end of the lever for lowering the cam to engage an upright on the end of a bell-crank lever located at the side of a track-rail and operate as set forth.

11. In an apparatus for operating a railway-switch, a lever fulcrumed to the under side and end portion of a car, a cam on the lower free end of the lever, a spring fixed to the lever and to the car to normally retain the cam on the end of the lever elevated, a treadle pivotally connected with the car and upper end of the lever, a spring between the end of the treadle and the end of the lever and means for lifting the front end of the lever for lowering the cam to engage an upright on the end of a bell-crank lever located at the side of a track-rail and operate as set forth.

12. In an apparatus for operating a railway-switch, two levers fulcrumed to the bottom and side portions of the end of a car and rigidly connected at their upper ends by a cross-bar, a treadle pivoted to the car and fixed to the center of the cross-bar that is flexibly connected with the upper end of the levers, cams on the lower ends of the levers and means to normally retain the cams elevated relative to an upright projecting up-

ward from a bell-crank lever aside of a track-rail as set forth.

13. In an apparatus for operating a railway-switch, two pairs of levers and each pair connected at their ends by a cross-bar and each lever pivoted to the under side of a car and provided with a cam on its lower free end, treadles pivoted to the cam and connected with the cross-bars and means to normally

retain the cams on the ends of the levers elevated relative to the uprights on the bell-crank levers at the sides of the track-rails as set forth. 10
